BOBBIN RECEPTACLE FOR LOOMS

Joseph C. Cobb and Eugene P. Floyd,
Tucapau, S. C.

Application November 21, 1941, Serial No. 419,838

10 Claims. (Cl. 139—255)

This invention relates to a bobbin receptacle for looms and more especially to a device of this character which is capable of being rotated into and out of bobbin receiving position relative to the loom shuttle box.

In automatic weft replenishing looms, a battery is usually provided for holding a plurality of filled bobbins, so that when the bobbin in the loom shuttle becomes empty, a replacement will be made without interfering with the operation of the loom. When a replacement is effected, a filled bobbin of yarn is transferred from the battery into the shuttle against the empty bobbin and thus the empty bobbin is expelled by the incoming filled bobbin. In order to collect the empty bobbins as they are expelled from the shuttle, a suitable can or receptacle is disposed below the loom shuttle box, preferably in an unobstructing position relative to the aisles between the rows of looms. At regular intervals a bobbin truck is passed down these aisles to take up the empty bobbins collected in each can or receptacle.

It is an object of this invention to provide an improved bobbin receptacle detachably mounted on a loom and normally positioned out of the loom aisles while in receiving position, but which is capable of being swung or rotated into the loom aisle when the collected bobbins are being removed therefrom.

It is another object of this invention to provide a bobbin receptacle of the class described in combination with an adjustable bracket structure whereby the receiving position of the receptacle may be varied relative to the loom shuttle box.

It is another object of the invention to provide a bobbin box made of fabric and having a ring adapted to be inserted around the rim for supporting the same, in a swinging position.

Some of the objects of the invention having been stated, other objects will appear as the description proceeds, when taken in connection with the accompanying drawings, in which—

Figure 1 is a schematic plan view illustrating the arrangement of a plurality of looms in a mill so as to provide an aisle space therebetween;

Figure 2 is an elevation, showing certain portions thereof in section, of a loom structure illustrating the improved bobbin receptacle;

Figure 3 is a sectional plan view taken along the line 3—3 in Figure 2, showing in dotted lines the position of the bobbin receptacle when in an inoperative position;

Figure 4 is a vertical sectional view taken along the line 4—4 in Figure 3;

Figure 5 is an isometric view of the bottom structure employed in the bobbin receptacle;

Figure 6 is an exploded isometric view showing the means for supporting the bobbin receptacle;

Figure 7 is an isometric view showing a slightly modified form of a bobbin receptacle supporting means in association with a loom frame.

Referring more particularly to the drawings, the numeral 10 denotes a portion of a loom frame 10 upon which is mounted a conventional battery bracket 11 in which is rotatably mounted a disk 12 as at 14. The periphery of the disk 12 is adapted to receive a plurality of filled bobbins of yarn 15 and during the operation of the loom 15 the disk 12 and these bobbins 15 are advanced step by step to a lowermost transfer position.

The transfer of the lowermost bobbin 15 is effected by a conventional L-shaped transfer arm 17 pivoted as at 18 to the battery bracket. One 20 leg of the L-shaped transfer arm 17 has a dog 19 pivotally secured to the lower end thereof, which dog is engaged during transfer by a suitable bunter 20 carried by oscillating loom lay 21. This loom lay has a shuttle box 22 on the upper 25 end thereof for receiving a shuttle 23. It will be noted that the lay 21 and the shuttle box 22 are disposed immediately below the lowermost bobbin 15 during a transfer. The parts in Figure 2 are shown while a transfer is being effected, and

30 at this time the lay 21 and bunter 20 are being moved to the left to thereby cause members 17 and 19 to rotate in a clockwise manner about the shaft 18. The rotation of member 17 serves to transfer the lowermost bobbin from the disk 12 35 into the shuttle 23. As the lowermost bobbin 15 enters the shuttle 23, the empty bobbin 15a is simultaneously removed therefrom, after which it falls downwardly against guide plate 25 and into a suitable receptacle therebelow. The parts, 40 thus far described are conventional in automatic replenishing looms but it is thought necessary to describe this much of conventional structure, to more thoroughly understand the purpose of the present invention.

45 It is very desirable that the receptacle which collects these expelled bobbins be supported by the loom frame, in a manner whereby the contents may be easily removed therefrom. It is equally desirable that the receptacle be normally placed in a non-obstructing position relative to the aisles or passageways between the rows of looms, so that trucks or other conveyances which are rolled down the aisle will not engage these receptacles. With these objects in view, the present receptacle has been swingably mounted

50

about a vertical axis so that the receptacle may be swung laterally into the loom aisle when the contents are being removed therefrom and may be rotated out of the loom aisle and beneath the shuttle box when in a bobbin receiving position.

Figure 1 illustrates a typical floor plan arrangement of looms in a mill. It is here seen that the loom frames 10 are arranged in rows, substantially alining their respective lays 21, thereby providing an aisle space 30 between the rows. This aisle space is substantially parallel to the lays of the loom, and is used for accommodating trucks and the like.

In order to provide a bobbin receptacle which will not obstruct this aisle 30 while in a bobbin receiving position, a novel type of bracket 32 has been secured to the side of loom frame 10 adjacent aisle 30 by any suitable means such as bolts 33. Bolts 33 are adapted to penetrate holes 34 in the bracket 32 and have the ends thereof threadably secured in the loom frame. The bracket 32 is U-shaped and when positioned on the loom frame the outstanding legs 32a and 32b are superposed in a horizontal position. These outstanding legs have vertically alined holes 35 therein for receiving a vertical leg 36 of a bag holding frame, broadly designated by the reference character 37. A horizontal portion 38 extends from the upper end of the vertical leg 36 and to this horizontal portion a downwardly inclined portion 39 is secured, which in turn has a horizontal portion 40 extending from its end. An upwardly inclined portion 41 extends from the end of portion 40, all of said portions 38, 39, 40 and 41 being bent so as to form a substantially rectangular frame. It will be noted that the end of portion 41 overlaps and rests upon the portion 38. Therefore, when it is desired to insert a bag upon the frame 37, it is only necessary to pull upwardly on the end of member 41 and insert the hem of the bag over the frame.

In the present disclosure, a bag 43 is provided, which is preferably made of some flexible material such as canvas, rubber or the like. The upper open end of the bag structure 43, has a hem 44 formed thereon for receiving the portions 38, 39, 40 and 41.

In order to make the bottom of the bag structure 43 wear-resistant, so that the falling of the empty bobbins 15a will not injure the same, a suitable rectangular bottom structure 45 is provided. This bottom structure may be made of any suitable material such as rubber, leather, wood, stiff fabric, metal or the like, and has secured thereto a U-shaped plate member 46 by any suitable means such as rivets or bolts 47. The legs of the U-shaped member 46 are secured to the vertical side-walls of the bag 43 by any suitable means such as bolts or rivets 48.

The bag holder together with its associated bag 43 is held in bobbin receiving position, that is bold line position, as shown in Figures 2 and 3 by means of a suitable notch 49 cut in the upper portion of bracket 32. This notch receives the horizontal portion 38 of the bag holding structure 37, and thereby releasably holds the bag and holder in position beneath the shuttle box in a bobbin receiving position. When it is desired to remove the contents from the bag structure, it is only necessary to lift the holder 37 and bag 43 a slight amount vertically, and then rotate the same about vertically alined holes 35 as an axis until the bag and frame are disposed within the aisle 30 between the looms. When in this position, an operator may remove the empty bobbins 75

from the receptacle or if desired he may detach the entire assembly from the bracket 32 and pour the empty bobbins into another receptacle.

Figure 7 shows a slightly modified form of bracket structure for supporting the bag. In this form, a U-shaped bracket 50 is adjustably secured to the side of end frame 10, by any suitable means such as stud bolts 51. These bolts penetrate the slot 52 in the bracket structure. Bracket 50 has horizontal legs 53 and 54, said leg having vertically alined holes 55 and 56 respectively therein for receiving leg 36 of the bag holder 37 previously described. The leg 53 has adjustably secured thereto a plate 57 which in turn has a pair of slots 58, each of which is penetrated by a screw 59, and these screws have their ends threadably secured in said leg 53 of the bracket. The upper edge of the plate 57 has a notch 60 therein into which the leg portion 38 of the bag holder or frame 37 is adapted to releasably fit when the bag is in a position for receiving bobbins from the shuttle box. The dotted line position of the leg member 38 shows the position of the frame when the parts are in this operative position, whereas the bold line position of parts 36 and 38 show the position of the bag when the same is rotated into the aisle and out from beneath the shuttle box.

When it is desired to vary the locked position that the bag or receptacle will occupy while beneath the shuttle box, it is only necessary to loosen the screws 59 and then reposition plate 57 and its associated notch 60. After this is done, the screws 59, of course, are again tightened. The vertical position of the bag structure and frame may be varied in a similar manner, that is, by loosening the stud bolts 51 and then bodily moving the bracket 50 vertically to the desired position.

In the drawings and specification, there has been set forth a preferred embodiment of the invention and although specific terms are employed, they are used in a generic and descriptive sense only and not for purposes of limitation, the scope of the invention being defined in the claims.

We claim:

1. In combination with a loom frame having a shuttle box, a bobbin replenishing and expelling mechanism associated with said shuttle box, a receptacle, means pivotally secured to the loom for supporting the receptacle beneath the shuttle box for receiving the expelled bobbin, said means being swingably mounted about a vertical axis whereby the receptacle may be rotated laterally from beneath the shuttle box when the bobbins are removed therefrom.

2. In combination with a loom frame having a shuttle box, a bobbin replenishing and expelling mechanism associated with said shuttle box, a receptacle beneath the shuttle box for receiving the expelled bobbin, and means for swingably mounting said receptacle on the loom to swing about a vertical axis whereby the receptacle may be rotated laterally from beneath the shuttle box when the bobbins are to be removed therefrom.

3. In combination with a loom frame having a shuttle box, a bobbin replenishing and expelling mechanism associated with said shuttle box, a receptacle pivotally mounted on the loom for swinging movement about a vertical axis and adapted to be positioned beneath the shuttle box for receiving the expelled bobbin, means on the loom for releasably locking said receptacle beneath the shuttle box, means for horizontally adjusting

the position of said releasably locking means to thereby vary the position of the receptacle while beneath the shuttle box.

4. In combination with a loom frame having a shuttle box, a bobbin replenishing and expelling mechanism associated with said shuttle box, a U-shaped bracket secured to one side of said loom frame and having vertically aligned holes in the outstanding legs thereof, an L-shaped rod having one leg rotatably mounted in said holes, a receptacle mounted on the other leg of said rod and adapted to be normally positioned beneath said shuttle box, whereby the receptacle may be rotated laterally from beneath said shuttle box when it is desired to remove the empty bobbins therefrom.

5. In combination with a loom frame having a shuttle box, a bobbin replenishing and expelling mechanism associated with said shuttle box, a U-shaped bracket secured to one side of said loom frame and having vertically aligned holes in the outstanding legs thereof, an L-shaped rod having one leg rotatably mounted in said holes, a receptacle mounted on the other leg of said rod and adapted to be normally positioned beneath said shuttle box, whereby the receptacle may be rotated laterally from beneath said shuttle box when it is desired to remove the empty bobbins therefrom, and means carried by said bracket for releasably locking said receptacle beneath the shuttle box.

6. In combination with a loom frame having a shuttle box, bobbin replenishing and expelling mechanism associated with said shuttle box, a U-shaped bracket secured to one side of said loom frame and having vertically aligned holes in the outstanding legs thereof, an L-shaped rod having one leg rotatably mounted in said holes, a receptacle mounted on the other leg of said rod and adapted to be normally positioned beneath said shuttle box, whereby the receptacle may be rotated laterally from beneath said shuttle box when it is desired to remove the empty bobbins therefrom, a notched plate for receiving said other leg of the L-shaped rod whereby the receptacle will be releasably locked beneath the shuttle box.

7. In combination with a loom frame having a shuttle box, a bobbin replenishing and expelling mechanism associated with said shuttle box, a U-shaped bracket secured to one side of said loom frame, and having vertically aligned holes in the outstanding legs thereof, an L-shaped rod having one leg rotatably mounted in said holes, a receptacle mounted on the other leg of said rod 55

and adapted to be normally positioned beneath said shuttle box, whereby the receptacle may be rotated laterally from beneath said shuttle box when it is desired to remove the empty bobbins 5 therefrom, a notched plate for receiving said other leg of the L-shaped rod whereby the receptacle will be releasably locked beneath the shuttle box, and means for horizontally adjusting the position of said plate to thereby vary the locked 10 position of the receptacle while beneath the shuttle box.

8. In combination with a loom frame having a shuttle box, a bobbin replenishing and expelling mechanism associated with said shuttle box, a U-shaped bracket secured to one side of said loom frame and having vertically aligned holes in the outstanding legs thereof, an L-shaped rod having one leg rotatably mounted in said holes, a receptacle mounted on the other leg of said rod and 15 adapted to be normally positioned beneath said shuttle box, whereby the receptacle may be rotated laterally from beneath said shuttle box when it is desired to move the empty bobbins therefrom, means carried by said bracket for releasably locking said receptacle beneath the shuttle box, and means for horizontally adjusting the position of said receptacle while beneath the shuttle box.

9. A quill container for looms comprising a flexible bag for receiving empty bobbins when expelled from the shuttle of a loom, said bag having a hem around its mouth, a rod having a vertically disposed leg, means for rotatably mounting said 35 leg on said loom for horizontal swinging movement of the rod, said rod having a horizontal portion bent into substantially the shape of a rectangle, the horizontal rectangular portion being adapted to be threaded through said hem to support the bag.

10. A bobbin receptacle for looms comprising a canvas bag having its mouth surrounded by a hem, a rod bent into substantially the form of a rectangle, and said rectangular portion being 45 adapted to be threaded through said hem to hold the bag mouth in open position, said rod having a laterally extending portion extending from the rectangular portion and having a downwardly and substantially vertically extending leg and 50 means on the loom engaging said leg for swingably mounting said rod and the bag supported thereby.
